UNITED STATES PATENT OFFICE.

JOHN R. BLAKESLEE, OF CLEVELAND, OHIO, ASSIGNOR TO THE AJAX MANUFACTURING COMPANY, OF CLEVELAND, OHIO, A CORPORATION OF OHIO.

PRESS.

1,362,595.

Specification of Letters Patent. Patented Dec. 21, 1920.

Application filed June 17, 1916. Serial No. 104,159.

To all whom it may concern:

Be it known that I, JOHN R. BLAKESLEE, a citizen of the United States, and a resident of Cleveland, county of Cuyahoga, and State of Ohio, have invented a new and useful Improvement in Presses, of which the following is a specification, the principle of the invention being herein explained and the best mode in which I have contemplated applying that principle, so as to distinguish it from other inventions.

The present improvements relate to a press designed for the manufacture of metal articles, particular attention having been paid to the balancing or counter-weighting of the main die slide and to improving the means for operating the same. My improved press is not only of simple construction, but has a very smooth and vibrationless operation. To the accomplishment of the foregoing and related ends, said invention, then, consists of the means hereinafter fully described and particularly pointed out in the claims.

The annexed drawings and the following description set forth in detail certain mechanism embodying the invention, such disclosed means constituting, however, but one of various mechanical forms in which the principle of the invention may be used.

In said annexed drawings:—

Figure 1 is a side elevation of a machine embodying my improvements; Fig. 2 is a plan view of a portion of the same; Fig. 3 is a transverse section and plan of another portion; and Fig. 4 is a diagram illustrating the disposition of parts and their operation.

The press mechanism proper, as well as the operating or driving mechanism therefor, is mounted on a substantial bed 1, it being understood that an anvil or lower die member will be also suitably mounted upon such bed, or base at 2, in line with the upper die-carrying member or slide 3, which alone is shown. The latter is held so as to be vertically reciprocable in a slideway 4 formed in a housing 5 of heavy construction firmly held to the machine frame and bed by horizontal and vertical tie-rods 6, as clearly shown in Figs. 1 and 3. The die-slide 3, which is shown in full lines in Fig. 1 in its raised position, and in dotted lines in its lowered position, is supported or suspended in the slideway just described by means of two links 7 and 8, pivotally connected together at their adjacent ends, the lower link

7 being in addition pivotally attached to said slide, and the upper link 8 to a shaft or pin 9 fixedly held in a cap-plate 10 that surrounds and covers the housing 5 (Fig. 1).

To one side of such slideway 4, and inclining downwardly away therefrom, is provided a second slideway 11, suitably supported on the machine frame and receiving a reciprocably mounted operating-slide 12. At its upper end slide 12 is connected with the toggle links 7 and 8, which support the die-slide 3, by means of two links 13 and 14 pivotally connected together, as clearly shown in Fig. 1, the pivotal joint between these two links being in turn connected with one end of a third link or rather lever 15, the other end of which is oscillatory about a fixed axis 16.

As a result of the foregoing construction, reciprocation of the operating slide 12 will obviously tend to straighten out, or break, the toggle joint formed by the two links 7 and 8, depending upon the direction of movement of said slide, and a corresponding vertical movement of the die-slide 3 will result. The two slides 3 and 12 being made substantially equal in weight, balance one another, so that only a relatively small amount of power is required to operate the die-slide, despite the fact that, in a press of this type, the latter is usually a very heavy member.

Moreover, by use of the oscillatory link 15 to support the intermediate pivotal connection between the two links 13 and 14 that connect the operating-slide with the toggle, it will be observed that the latter of said links is caused to move in a substantially horizontal line at all times, and thus apply the pressure exerted by the operating-slide 12 in the most effective fashion to such toggle, whether for opening or closing the same.

The operating-slide 12 may be reciprocated by any suitable means, those shown in Figs. 1 and 2 being typical merely. As there illustrated, a crank-shaft 17 driven by means of gears 18 and 19 from a pulley shaft 20 is connected through the medium of a rod or pitman 21 adapted to be disconnected at will from said slide, as described in United States Letters Patent No. 737,065, dated August 25, 1903. The construction includes a thrust arm or lock 22 pivoted to the slide about an axis 23, such arm being provided with a face normally bearing against a block 24.

24 on the end of the pitman, as a result of which it will be seen that by simply throwing up said arm the pitman is allowed to reciprocate without effecting any movement 5 of the slide.

By counterbalancing the die-slide and operating-slide in the fashion exemplified in the machine just described, smoothness and ease of operation are secured in a degree impossible with prevailing designs of press mechanism. At the same time the arrangement of the toggle, and of the links connecting the operating slide therewith, is such as to utilize most advantageously the power 10 applied to said operating slide. Withal, the machine is of simple and compact construction, occupying relatively small space and having the driving mechanism as well as the die slide readily accessible.

15 Other modes of applying the principle of my invention may be employed instead of the one explained, change being made as regards the mechanism herein disclosed, provided the means stated by any of the 20 following claims or the equivalent of such 25 stated means be employed.

I therefore particularly point out and distinctly claim as my invention:—

1. In mechanism of the character described, the combination of a vertically movable die slide, toggle mechanism connected thereto for operating the same, and a second slide movable in a direction at an acute angle to said die slide, said toggle 30 mechanism being also connected to said second slide and being operated by movement of the same, and said second slide being constructed to counterbalance said die 35 slide.

40 2. In mechanism of the character described, the combination of a vertically movable die slide, toggle mechanism connected thereto for operating the same, a second slide movable in a direction at an 45 acute angle to said die slide, said toggle mechanism being connected to said second slide and being operated by movement of the same, and said second slide being constructed to counterbalance said die 50 slide, a rotatable shaft, and means operated by said shaft and adapted to reciprocate said second slide.

55 3. In mechanism of the character described, the combination of a vertically movable die slide, toggle mechanism connected thereto for operating the same, a second slide movable in a direction at an acute angle to said die slide, said toggle mechanism being connected to said second 60 slide and being operated by movement of the same, and said second slide being constructed to counterbalance said die slide, and a rotatable crank-shaft operatively connected with said second slide.

65 4. In mechanism of the character de-

scribed, the combination of a vertically movable die slide, toggle mechanism connected thereto for operating the same, a second slide movable in a direction at an acute angle to said die slide, said toggle 70 mechanism being connected to said second slide and being operated by movement of the same, and said second slide being constructed to counterbalance said die slide, a continuously rotating crank-shaft normally 75 operatively connected with said second slide, and means adapted to disconnect said crank-shaft from said last-named slide.

5. In mechanism of the character described, the combination of two slides movable in different directions at an angle to each other and constructed to exert the same vertical pressure to counter-balance each other, toggle mechanism connecting said slides, and means adapted to reciprocate 80 85 one of said slides, thereby also actuating the other.

6. In mechanism of the character described, the combination of two slides movable in different directions at an angle to each other and constructed to exert the same vertical pressure to counter-balance each other, one of said slides being adapted to receive a die, toggle mechanism connecting said slides and adapted to multiply pressure exerted by the other of said slides in 90 transmission to such die receiving slide, and means for reciprocating such other slide. 95

7. In mechanism of the character described, the combination of a vertically movable die-slide; a counter-balancing operating-slide movable on a line inclined to the path of movement of said die-slide; and means connecting said slides, including toggle-links supporting said die-slide and 100 two other links connecting said operating-slide with said toggle-links. 105

8. In mechanism of the character described, the combination of a vertically movable die-slide; a counter-balancing operating-slide movable on a line inclined to the path of movement of said die-slide; and means connecting said slides, including 110 toggle-links supporting said die-slide, two other links connecting said operating slide 115 with said toggle-links, and means controlling the movement of said other links.

9. In mechanism of the character described, the combination of a vertically movable die-slide; a counter-balancing operating-slide movable on a line inclined to the path of movement of said die-slide; and means connecting said slides, including 120 toggle-links supporting said die-slide, two other links connecting said operating slide 125 with said toggle-links, and a lever oscillating about a relatively fixed axis and connected with said other links so as to control the movement thereof.

10. In mechanism of the character de- 130

scribed, the combination of a vertically movable die-slide; a counter-balancing operating-slide movable on a line inclined to the path of movement of said die-slide; and
5 means connecting said slides, including toggle-links supporting said die-slide, two other pivotally connected links attached to said operating-slide and the other to said toggle-links, and a lever oscillatory about a
10 relatively fixed axis and connected with

said other links at the point of their pivotal connection, whereby the one attached to said toggle-links is caused to move in a substantially horizontal direction.

Signed by me, this 12th day of June, 1916. 15

JOHN R. BLAKESLEE.
